ANTITHEFT CONTAINER

Frank S. Butke and William Fairchild,
Evansville, Ind.

Application September 19, 1940, Serial No. 357,476

4 Claims. (Cl. 232—42)

This invention relates to an anti-theft container, and has for one of its objects the production of a simple and efficient container for supporting empty bottles in a manner whereby the empty bottles may not be released until merchandise is placed within the container and the container is closed by a person making delivery.

A further object of this invention is the production of a simple and efficient locking rod for locking the lid of a container in a closed position.

In the drawings:

Figure 1 is a front elevational view of the container;

Figure 2 is an end elevational view of the container;

Figure 3 is a vertical sectional view taken on line 3—3 of Figure 1;

Figure 4 is a vertical sectional view taken on line 4—4 of Figure 2;

Figure 5 is a horizontal sectional view taken on line 5—5 of Figure 4;

Figure 6 is a vertical sectional view similar to Figure 4 showing the locking rod in a locked position;

Figure 7 is a horizontal sectional view taken on line 7—7 of Figure 6;

Figure 8 is a horizontal section taken on line 8—8 of Figure 2;

Figure 9 is a fragmentary perspective view of a portion of the locking rod; and

Figure 10 is a sectional perspective view of a portion of the container showing one of the hanger brackets.

By referring to the drawings, it will be seen that 10 designates the container which may be of any suitable or desired shape but is preferably of a rectangular structure. The container 10 is provided with a hanger 11 upon the bottom thereof, which hanger 11 comprises a floor plate 12 having notches 13 formed therein with the entrance openings of the notches 13 extending outwardly toward the front of the container. The side edges of the notches 13 are adapted to fit under the bead 14 of an empty bottle 15 and support the empty bottle 15 in a suspended position below the container 10. The hanger 11 is provided with a front wall 16 having apertures 17 formed therein through which the upper ends of empty milk bottles may be extended for suspending the milk bottles from the bottom of the container 10 in the manner shown in Figure 1, and these apertures 17 are properly designed as to shape to receive the beads 14 of the empty bottles 15.

A locking bolt 18 is slidably mounted within

the container 10 and is supported in position by means of a guide 19. This locking bolt 18 carries a horizontal bar 20 which is adapted to extend longitudinally of the hanger 11 near the floor portion 12 thereof in a manner shown in Figures 1 and 4, and across the entrance openings of the notches 13 in a manner as shown in detail in Figures 3 and 8. When the horizontal bar 20 is in this position the empty container or bottles 15 will be held within the notches 13 and will be prevented from being removed. The horizontal bar 20 spans the entrance openings of the notches 13, as shown. The hanger 11 is provided with end plates 21 which terminate short of the front wall 16 to provide openings 22 into which the ends 23 of the horizontal bar 20 fit, in this way providing a guide for the ends of the horizontal bar 20. The bottom portion of the hanger 11 is preferably braced by means of a hanger bracket 24 which may be secured to a suitable support, as at 25, shown in Figure 2. The container 10 may also be secured to a support by means of the hanger bracket 26, as shown in Figures 2 and 10.

The upper end of the locking bar 18 is adapted to extend into an aperture 27 formed in a keeper plate 28 secured near one side edge of the horizontal sliding top or lid 29. This plate 28 extends only for approximately one-half of the length of the top 29 and constitutes also a means for limiting the sliding of the top or lid 29 in one direction, as shown in dotted lines in Figure 4. The lid or top 29 is provided with a flange 30 at one end to facilitate the gripping of the lid or top 29 by the fingers of an operator.

A primary latching trigger 31 is pivotally secured at or near the bottom of the container 10 and carries a coil spring 32 to normally hold the trigger 31 for frictional contact with the locking bar 18. The trigger 31 is provided with an extended outer end 33 whereas the inner end of the trigger 31 is adapted to control the locking rod 18, as shown in Figures 5 and 7. This locking rod 18 is provided with a notch 34 near the lower end of the rod. A second trigger 36 is pivotally secured at or near the bottom of the container 10 and is provided with an outwardly extending end 37 and an inwardly extending end 38, the end 38 being adapted to frictionally engage the locking rod 18, a coil spring 39 being provided for the trigger 36 to provide this frictional contact.

When the container 10 is empty, and the empty milk bottles or containers are suspended from the hanger 11, as shown in Figure 4, the locking

rod 18 is in a retracted position and the primary trigger 31 engages the notch 34 thereby holding the locking rod 18 in this retracted position. The lid or cover 29 may then be moved to the position shown in dotted lines uncovering approximately one-half of the upper end of the container 10 to permit a delivery man to place a milk bottle or other article within the container 10, as shown in Figure 6 against the extension 33 of the trigger 31 to move the trigger 31 out of engagement with the notch 34. The delivery man may then close the lid 29 and manually move the horizontal rod 20 and locking bar 18 upwardly to the position shown in Figure 6 where the inner end 38 of the trigger 36 will engage the notch 34 in the locking bar 18 and hold this locking bar in this position to prevent the lid 29 from being opened. When the locking bar is in a raised position the milk bottles suspended from the hanger 11 may be easily removed since the horizontal bar 20 will be raised to the position shown in Figure 6 above the bead 14 of the suspended bottle or bottles 15.

The box will then be locked in a closed position until the occupant of the dwelling opens the door or window 40 whereupon the locking bolt 41 carried by the window frame 42 may be moved to the dotted position shown in Figure 2, and withdrawn from the keeper 43, which keeper 43 is carried by the vertically extending and slidable gate 44 mounted upon the container 10. When the vertically sliding gate 44 is raised, the occupant of the dwelling may reach into the container and remove the articles therefrom, and may also release the trigger 36 from engagement with the notch 34 to lock empty bottles 15 within the hanger after the bottles have been placed in position. The upward movement of the gate 44 may be limited by means of a stop 45 carried within the container 10, which stop may be engaged by means of a suitable hook 46 carried by the bottom of the gate or door 44. A flange 46 is carried by the upper end of the gate or door 44 to facilitate the movement of the gate. The gate or door 44 as well as the lid or cover 29 may be slidably mounted in any suitable or desired manner without departing from the spirit of the invention, one form being that of the rolled flange structure shown in the drawings.

As indicated in Figure 3, the container as well as the doors thereof may be insulated by means of insulating panels 47, and the operating parts of the mechanism may be then suitably located to accommodate this insulation material. Any suitable type of insulation may be employed, as desired, and the device may be effectively used with or without such insulation, the insulation being preferably provided where the container is subjected to severe temperature changes.

It should be understood that the present device in the nature of the container 10 may be placed adjacent a door or window without departing from the spirit of the invention, which window or door may engage the sliding bolt 41 in a manner similar to that shown in Figure 2. When the door or window is closed, the bolt will be retained in a closed or locked position and may not be released until the door or window is opened.

When the empty milk bottles 15 have been placed in the hanger and the bar 20 is in the position to close the front or open ends of the notches 13 as shown in Figure 1, the trigger 31 will engage the notch 34 and hold this bar in this position and the containers or bottles 15 will be held

against accidental removal until the lid 29 is opened and the trigger 31 is disengaged from the notch 34 by the delivery man who places a milk bottle against the latch trigger 31 for releasing the latch trigger 31. When a milk bottle or other article is placed in the container 10 against the end 33 of the latch trigger 31, the trigger 31 may be moved out of locking position with the locking rod 18, and when the lid 29 is closed, the horizontal bar 20 and rod 18 may be moved upwardly for locking engagement with the keeper plate 28 and the end 38 of the second trigger 36 will lock the locking rod 18 in a locking position in engagement with the lid 29. The container cannot then be opened until the operator raises the window 40 and releases the bolt 41 from the gate 44.

It should be understood that the container may be used as a receptacle for milk, butter, eggs and other dairy products.

Certain detail changes in the mechanical construction, and arrangement of parts may be employed without departing from the spirit of the invention, so long as such changes fall within the scope of the appended claims.

Having described the invention, what is claimed is:

1. A device of the class described comprising a container adapted to receive articles, the container having an open top, the container having a cover adapted to slide across the top of the container to and from a closed position, a hanger suspended below the container and adapted to engage the neck of a milk bottle to suspend a milk bottle below the container, said hanger comprising a frame having notches designed to receive the bead and neck of a milk bottle and being provided with forward entrance openings, a vertically movable horizontal locking bar adapted to extend across the entrance openings formed in the hanger to retain a milk bottle in the hanger, means for locking the horizontal bar in a retaining position, and means carried by the horizontal bar for engaging the cover to hold the cover in a closed position against sliding movement when the horizontal bar is raised to a releasing position.

2. A device of the class described comprising a container having a slidable cover, the cover having an apertured keeper plate, a hanger suspended below the container, the hanger having article-receiving apertures, the article-receiving apertures having entrance openings in one side thereof, a horizontal article-retaining rod carried by the hanger and adapted to close the entrance opening when the horizontal rod is in one position, a vertically extending locking bar carried by the horizontal retaining rod and adapted to engage the apertured keeper plate when the horizontal rod is raised to free the entrance openings in the hanger to hold the cover in a locked position, the keeper plate limiting the sliding movement of the cover in one direction, the vertical locking bar having a notch formed therein, and spring-latch triggers adapted to selectively engage the notch to hold the rod in selected positions.

3. A device of the class described comprising a container having an open top, a cover for closing said open top, a hanger suspended below the container, the hanger having article-receiving apertures, the article-receiving apertures having entrance openings in one side, a closure means for said entrance openings movable to an article-retaining position to retain articles in the article-receiving apertures, releasable means for locking

the closure means in an article-retaining position, means carried by the closure means and movable to an article-releasing position for engaging said cover to lock the cover in a closed position to prevent access to the interior of said container by unauthorized parties, means for locking said last-mentioned means in the last-mentioned position, and a second door operable by an authorized party for permitting access to the interior of the container for facilitating removal of the contents of the container and facilitating the release of said last-mentioned locking means.

4. A device of the class described comprising a container having an open top, a cover for closing said open top, a hanger suspended below the container, the hanger having article-receiving apertures, the article-receiving apertures having entrance openings in one side, a closure means for

5 said entrance openings movable to an article-retaining position to retain articles in the article-receiving apertures, an automatic spring-pressed latch for locking the closure means in an article-retaining position, means carried by the closure means and movable to an article-releasing position for engaging said cover to lock the cover in a closed position to prevent access to the interior of said container by unauthorized parties, an automatic spring-pressed latch for locking said last-mentioned means in the last-mentioned position, and a second door operable by an authorized party for permitting access to the interior of the container for facilitating removal of the contents 10 of the container and facilitating the release of said last-mentioned locking means.
